UNITED STATES PATENT OFFICE.

ARTHUR E. COLGATE, OF NEW YORK, N. Y.

PICTURE APPARATUS.

No. 853,441.

Specification of Letters Patent.

Patented May 14, 1907.

Application filed February 27, 1907. Serial No. 359,564.

To all whom it may concern:

Be it known that I, ARTHUR E. COLGATE, a citizen of the United States, residing at the city, county, and State of New York, (post-office address No. 251 West One Hundred and Twenty-ninth street,) have invented certain new and useful Improvements in Picture Apparatus, of which the following is a full, clear, and exact description.

My invention relates to picture apparatus, and the object of my invention is to provide a means for illustrating, for example,—one complete scene or view, with means for at once showing to the user relatively enlarged detail views of certain points of important interest, which, because of the scale upon which the main view is taken, cannot be fully comprehended or clearly seen in such view. For example, in the drawings I have shown a mountain scene in a mining district. At several points shaft or tunnel openings appear. In this particular instance, these openings may be assumed to be the points of especial interest, and the user has merely to turn back the leaf, the free edge of which lies closest to the opening which he is particularly interested in, whereupon there is exposed beneath the leaf just turned back an enlarged view of said detail. This idea may be extended to many scenes and views, the main illustration continuing over two or more superposed leaves when the same are closed.

In the drawings, Figure 1 is a plan view of an open booklet, the cover-leaf of which is turned back to expose the illustrated portion showing the main view. Fig. 2 is a similar view, with the cover-leaf partially broken away, and showing a portion of the main view as well as a relatively enlarged view of one of the details. Fig. 3 is an edge elevation of the parts shown in Fig. 2.

A is the back cover; A' is the front cover. These covers may or may not be employed, as desired, but furnish a protection for the picture apparatus, and also furnish a space for the publication of any description it may be desired to employ with reference to the particular scene depicted.

B, C, D, E and F are a plurality of connected superposed leaves, the free edges of which are non-registering. G represents the backing or binding for the connected edges of said leaves.

1, 2, 3 and 4 illustrate points of particular interest. The main scene exposed (when the several leaves are turned down) is a mountain

view or landscape. The points of particular interest represent shaft openings or tunnels extending into the earth. Upon turning back the several leaves D, E and F, for example, as shown in Figs. 2 and 3, a relatively enlarged view C' is uncovered, which gives to the reader a comprehensive illustration of the detail represented at 2. It is preferable to have a portion of the picture at the edge of each overlying leaf reproduced on the underlying leaf and extending slightly under the edge of the first-mentioned leaf, for example, as indicated in the reproduction of detail numbered 2 on leaf C in Fig. 2. The purpose of this is to prevent any substantial impairment of the view as a whole in the event the edges of the several leaves might be curled up slightly. This, it will be understood, is merely a preferable construction, as of course that portion of the picture on any one leaf might stop abruptly at the edge of the overlying leaf. While the other detail views are not shown in the drawings, obviously the relatively enlarged view of the detail numbered 1 would be exposed upon lifting and turning back the leaf C; and the detail at 3 by turning back the leaf E; and the detail at 4 by turning back the leaf F.

It will be seen that in the preferable form of my invention, the edge of a particular leaf may lie so closely adjacent to the detail, the enlarged view of which it covers, that it acts as a key or index to the particular view underneath the same. For example, the free edge of the leaf D lies closely adjacent to the tunnel opening 2. By turning back this leaf D, the reader will find that the relatively enlarged illustration C' shows, in a comprehensive manner, the shaft opening 2 with a track entering the same, with a car on said track. As suggested, it is immaterial what the main view is, since, whatever it may be, the scale may be such as to make it necessary to illustrate details on an enlarged scale, and this may be done very effectively and compactly by the means above described.

What I claim is—

1. In a picture apparatus a plurality of connected superposed leaves the free edges thereof being non-registering, an illustration extending over the exposed surfaces of two or more of said leaves, and a relatively enlarged view of a detail of such illustration located on such a part of one of said leaves as is normally covered by another.
2. In a picture apparatus a plurality of

connected superposed leaves the free edges thereof being non-registering, an illustration extending over the exposed surfaces of two or more of said leaves, and a relatively enlarged view of a detail of such illustration located on such a part of one of said leaves as is normally covered by another, the free edge of the over-lying leaf being located adjacent to the detail, the enlargement of which is to be exposed by turning back said leaf.

3. In a picture apparatus, a plurality of connected superposed leaves, the free edges

thereof being non-registering, an illustration extending over the exposed surfaces of two or more of said leaves, and a relatively enlarged view of a detail of such illustration carried by one of said leaves and covered when the leaves are in position to expose the main illustration. 15

ARTHUR E. COLGATE.
